UNITED STATES PATENT OFFICE.

GEORGE JIENCKE AND ALEXANDER MCKEE, OF PHILADELPHIA, PA.

SPRING-MOTOR.

SPECIFICATION forming part of Letters Patent No. 315,946, dated April 14, 1885.

Application filed February 11, 1885. (No model.)

To all whom it may concern:

Be it known that we, GEORGE JIENCKE, a subject of the Emperor of Germany, and ALEXANDER MCKEE, a citizen of the United States, 5 both residing in Philadelphia, in the county of Philadelphia and State of Pennsylvania, have invented certain new and useful Improvements in Spring-Motors, of which the following is a description, reference being had 10 to drawings hereto annexed.

Our invention pertains to that class of spring-motors in which there is a number of springs used, and in such a manner as to yield the power of one spring only, whereas the time 15 through which this power acts is proportional to the number of springs employed, and also to the means employed for the transmission of the power of the springs, also to the winding-gear and the speed-regulating mechanism.

With reference to drawings, Figure 1 is a vertical section through the center line. Fig. 2 is a vertical side view. Fig. 3 is a plan showing the gearing. Fig. 4 is a detached view of one of the springs, illustrating at the 20 same time the mode of fastening the springs. Figs. 5 and 6 represent detailed views of a mechanism belonging to the winding-gear. Fig. 7 is a view from the back to show the mechanism for regulating the speed. Fig. 8 25 shows the same mechanism, looking from the right-hand side. Figs. 9, 10, 11, and 12 are views of details belonging to the speed-regulating mechanism.

In Fig. 1, A' A'' are the top and bottom 30 plates of the motor, which are connected by the four stays B' B'' B''' B'', the whole forming a rigid frame for the springs and their attachments.

C' C'' C''' C'''' are flat spiral springs, of which 35 C' is stationary, whereas C'' C''' C'''' are capable of revolving around the vertical center stay, B''.

D' D'' D''' are shields or frames to carry the movable springs C'' C''' C''''. As shown in Fig. 45 4, they have three arms or spokes, one of these arms carrying a pin, a, to receive the outside end of the spring, whereas the other two spokes have square projections b cast on to check the expansion of the springs beyond a certain 50 limit, to prevent their rubbing against the

vertical stays B', &c., B'', when revolving. The hubs of these shields are shaped cylindrically, and project into the inside coil of the next spring below, offering means of attachment to the inside end of this spring. To explain this arrangement more fully, we may take the case of shield D'. The pin a receives the outside end of spring C'', whereas its hub, projecting into the inside coil of spring C', offers means of attachment to the spring C', 55 and the two springs C'' and C' are connected. The springs C'' and C'' and C''' and C'''' are connected in the same manner, the shield D always connecting the outside end of one spring to the inside end of the next spring below. 60 It will be observed that all springs have to be wound in the same direction. The pin a and the projections b b may be cast solid with the shields. The shields D' D'' D''', which are capable of revolving freely on the vertical center shaft, B'', are supported by rings or collars, Fig. 1, E' E'' E''', pinned or otherwise fixed onto the center stay, B'', and which fit into recesses in the hubs of the shields D' D'' D''', in the manner shown in Fig. 1, their object being the reduction of friction. The space between the top of the springs and the bottom of the next shield above should not be greater than just to give sufficient clearance for the springs to work. It will be seen that the number of springs does 65 not affect the principle involved, and may be increased or diminished as necessity demands. The top spring, C''', is attached to the hub of a wheel, F', which rests on the collar E'''. It may not be thought necessary to support each 70 individual spring in using a large number of them, but several of them may be supported in this manner by suitable rings, E. The bevel-wheel F' gears into the two beveled pinions F'' F''', which are arranged diametrically 75 opposite each other, as shown in Figs. 1 and 3. The beveled pinion F'' is fast on a movable shaft, G', said shaft G' carrying also a spur-wheel, J', which is capable of revolving freely in one direction on the shaft G', its motion in the opposite direction being prevented by an engaging mechanism shown in Figs. 5 and 6, and to be described hereinafter. Said engaging mechanism is placed in a recess on the face of the wheel J'. All the shafting of 80 85 90 95 100

the gearing is supported by the brackets K' K'' K''' on the top plate, A'. The wheel J' gears into a pinion, i', Fig. 3, on the shaft G'', on which it is fastened, commonly with the spur-wheel J'', which in its turn drives a pinion, i'', on the shaft G'''. Said shaft G''' carries the wheels J''' J^{IV} J^V J^{VI}, which are loose on said shaft G''', and capable of turning independently of each other, and gearing into corresponding wheels, i''' i^{IV} i^V i^{VI}, on the shaft G^{IV}, on which they are fixed. The shaft G^{IV} also carries a pulley, L, which connects by means of a belt to the machine that is to be run by the motor. The wheels J'''', &c., J^{VI} on the shaft G''' are provided with bushings, one projecting through the other in the manner shown in Fig. 1. A detailed view of wheel J^{VI} is shown in Figs. 11 and 12, which also illustrates the construction of the wheels J''' J^{IV} J^V J^{VI}. Said bushings have rings fitted onto them which are provided with tooth projections c' c'' c''' c^{IV}, as shown in Figs. 1, 11, and 12. A coupling, M, which is provided with similar tooth projections to correspond with those on the bushings of the wheels J'''', &c., J^{VI}, is arranged to slide longitudinally and without revolving on the shaft G''', and can be brought into contact with either of the tooth projections c' c'' c''' c^{IV} of said bushings, thus imparting the rotary motion of the shaft G''' to either of the wheels J'''', &c., J^{VI}.

The construction of the coupling M is shown in Figs. 9 and 10.

The mechanism for operating the coupling M consists in a two-armed lever, N, Figs. 7 and 8, which embraces the coupling M in an annular recess on said coupling, and is provided with two rollers, O' O'', to reduce the friction of the coupling M against the lever N. Said lever N is mounted on a shaft, P, which is carried by the brackets K^{IV} K^V. A lever, R', is mounted on the same shaft P, which connects by means of a rod, R'', to a treadle, R'', Figs. 7 and 8, which may be the treadle of a sewing-machine, if the motor is used as a sewing-motor. The lever R' is provided with a notch-sector, S, as shown in Fig. 7, which forms part of a mechanism intended to keep the coupling M in such a position as to enable the tooth projections of the coupling M to engage themselves with some of the tooth projections c' c'' c''' c^{IV} on the bushings of the wheels J'''', &c., J^{VI}. A bell-crank lever, T' T'', Figs. 7 and 8, which is supported by a pin on a bracket, U, screwed onto the top plate, A', and carries a little roller, V, on its double arm T', to fit into the notches 1 2 3 4 of the sector S, serves the purpose of arresting said notch-sector S, and with it the lever N and the coupling M, in positions as to properly engage said coupling M with the tooth projections c' c'' c''' c^{IV}. The arm T'' of the bell-crank lever T' T'' has a tension-spring, W', attached to it, which is suspended from the top plate, A', of the frame, and which spring is adjusted to exert a constant pressure of

the roller V on the arm T', against the notch-sector S, to offer a certain amount of resistance to the shifting of said sector S. A spiral spring, W'', is placed on the shaft P, Figs. 3 and 8, which carries the weight of the rod R'', connecting with the treadle R'', and has also the tendency to throw the coupling M, when it is in contact with the tooth projection c' of the wheel J'', on the face of said wheel J'', the corresponding notch, 1, in the sector S being cut out for this purpose, as shown in Fig. 7. Another spiral spring W'', is arranged on the shaft G''', inside of the coupling M, Fig. 1. In the position shown of coupling M the spring W'' is loose; but as the coupling travels over to the tooth projection c' of the wheel J'' the bottom of said coupling will strike against the spring W''' and compress it, and its friction against the bushing of the wheel J^{VI} will act as a retarding-brake when the coupling is in contact with the wheel J'''. The winding mechanism consists in a bevel-pinion, F'', gearing into the bevel-wheel F', and fastened onto the shaft G', Fig. 1, which is provided with a square projection to receive a winding crank or key, and of an engaging mechanism, as shown in detached views in Figs. 5 and 6.

As stated above, the face of the wheel J' is recessed out to receive the engaging mechanism. The latter consists in a ring, X', with three or more tooth projections, such as shown in Figs. 5 and 6. Said ring is fast in the recess of the wheel J'. A little frame, Z', is shaped as shown in Figs. 5 and 6, with a tooth projection to correspond with those of the ring X'. Inside of the frame Z' there is a little eccentric, Y', which is keyed onto the shaft G', as shown. The frame Z' is prevented from getting out of its position inside of the ring X' by the bevel-wheel F'.

Having thus described the detailed construction of our device, we shall now proceed to explain the functions of the various mechanisms, and will commence by examining the actions of the springs by allowing the wheel F' to complete one revolution, it being supposed that the springs are wound up. The springs C' C'' C''' C^{IV} will all have the same amount, and when the tension of one of the springs is reduced the other springs will give up a part of their tension to add it to that of the first spring, the tension of which has been reduced through the medium of the shields D' D'' D'', which form the connection between the springs, as explained above, thus restoring the state of equilibrium. If now the wheel F' completes one revolution, the spring C^{IV} will give off an amount of tension proportional to one revolution, but the spring C'' will restore three-quarters of this tension, and the spring C''' in its turn will restore two-quarters of this tension in the spring C'', and finally spring C' will restore one-quarter in the spring C'; each spring thus giving off a one-quarter of that amount of tension necessary to produce

one revolution of the wheel F'' , and in this manner the springs will operate till their tension is exhausted. A similar process in the reverse direction takes place when winding 5 up the springs. The tension that is imparted to the first spring will at all times distribute itself equally through the whole train of springs. The winding is done by turning the shaft G^v on which the beveled pinion F'' rides 10 by means of a crank or key which will impart motion to the wheel F' on which the spring C^v is fast. The bevel-pinion F'' will run idly with the motion of the bevel F' , and the little frame Z' , Fig. 6, will slide freely on the 15 teeth of the ring X' without engaging with them, the position of the eccentric Y' being such as to enable the frame Z' to pass by the teeth of the ring X' .

Fig. 6 clearly illustrates the function of this 20 mechanism when the motor is being wound up, the arrow indicating the direction in which the shaft G' , with the eccentric Y' , turns. When the shaft G' turns in the opposite direction, as indicated in Fig. 5—that is, when 25 the springs are running down—the eccentric Y will then wedge the frame Z' against the teeth of the ring X' and engage it with them in the manner shown. The ring X' being fast in the recess of the wheel J' will cause said 30 wheel J' to revolve with the shaft G' , which derives its motion, through the bevels F'' and F' , from the springs. The rotary motion of the wheel J' is transmitted through the pinion i'' and the wheel J'' on the shaft G'' , and the pinion i'' to the shaft G''' . The coupling M , turning 35 with the shaft G''' , will impart its motion to one of the wheels $J''' J^{iv} J^v J^{vi}$, which in its turn will transmit motion to the shaft G^{iv} , on which the wheels $i''' i^{iv} i^v i^{vi}$ are mounted, 40 commonly with the pulley L , which connects by means of a belt with the machine or apparatus that is to be run by the motor. In order to properly describe the functions of the "speed-regulator," as we may designate the wheels 45 J''' , &c., J^{vi} , the coupling M , and the mechanism for shifting the latter, let it be supposed that the coupling M is in contact with the tooth projection c' on the wheel J''' , with the coupling M pressed onto the face of said 50 wheel J''' by the spring W'' on the shaft P , in which position the spring W'' on the shaft G''' is compressed between the coupling M and the bushing of the wheel J^{vi} ; then the roller V of the bell-crank lever $T' T''$, Fig. 7, will be at 55 the top extremity of the notch-sector S , the notch 1 being cut away, as explained above, and shown in Fig. 7.

The combined pressure of the coupling M against the face of the wheel J''' and that of the 60 spring W'' against the bushing of the wheel J^{vi} is supposed to be strong enough to produce sufficient resistance to stop the motion of the gearing. By a slight pressure of the foot on

the treadle R'' the coupling M will be moved back and the wheel J''' be relieved of its resistance and be allowed to revolve. The only resistance now to be overcome outside of the unavoidable resistance of the gearing will be that caused by the spring W''' on the shaft G''' against the bushing of the wheel J^{vi} . The 65 more the coupling M is removed from the wheel J''' the less the resistance will be, and the greater the speed at which the motor runs. The spring W''' is so adjusted as to be entirely relieved when the roller V of the bell-crank 70 lever $T' T''$ touches the partition between the notches 1 and 2 of the notch-sector S , Fig. 7. If it is desired to still further increase the speed, an additional pressure on the treadle 75 E'' will cause the roller V to jump from notch 80 1 to notch 2 and throw the coupling M from the tooth projection c' of the wheel J''' into contact with the tooth projection c'' of the wheel J^{iv} , which throws the latter into gear and makes the wheel J''' run idly. In the 85 same way the coupling M may be brought into contact with any of the wheels $J''' J^{iv} J^v J^{vi}$ and the speed be correspondingly increased or diminished as necessity demands.

What we claim as new, and desire to secure 90 by Letters Patent, is—

1. In a spring-motor, the combination of a series of springs to a continuous train, with shields or frames, as described, a central rod provided with rings or collars to offer support 95 to each individual spring or any number of them, the whole being supported by a rigid frame, substantially as and for the purpose described.

2. In a spring-motor, the combination, with 100 a series of springs supported and connected with each other in the way described, of a train of gearing supported by brackets arranged as described, and mechanism for changing the speed of the gearing, consisting in a 105 coupling, M , a cone of wheels, $J''' J^{iv} J^v J^{vi}$, with bushings and projections $c' c'' c''' c^{iv}$, and a cone of wheels, $i''' i^{iv} i^v i^{vi}$, on a shaft, G^{iv} , and levers N and R' , with a sector, S , on the shaft P , bell-crank lever $T' T''$, with roller 110 V , and spring W' , substantially as and for the purpose described.

3. In a spring-motor, the combination, with 115 a series of springs arranged and supported as described, a rigid frame and a train of gearing, of the winding mechanism consisting in the bevel-wheels $F' F'' F'''$, supported as described, and the ring X' in the recess of the wheel J' , the frame Z' , the eccentric Y' on the shaft G' , substantially as and for the purpose 120 described.

GEORGE JIENCKE.
